UNITED STATES PATENT OFFICE.

HENRY M. GREEN, OF LOS ANGELES, CALIFORNIA.

PACKING CONSTRUCTION FOR PUMPS.

Application filed September 15, 1919, Serial No. 323,969. Renewed April 17, 1922. Serial No. 553,930.

To all whom it may concern:

Be it known that I, HENRY M. GREEN, a citizen of the United States, residing at Los Angeles, in the county of Los Angeles, State 5 of California, have invented certain new and useful Improvements in Packing Construction for Pumps, of which the following is a complete specification.

The present invention relates to packing 10 means for pumping apparatus, and aims to provide an improved structure of this character one feature of which is the utilization of the weight of the liquid above the packing for maintaining the same tightly 15 compressed.

It is also an object of the invention to devise a pump packing structure in which both the weight of the liquid above the packing and the weight of the pump plunger member are rendered available for action in compressing the packing.

It is further sought to provide a construction in which automatic means are included for the purpose of latching and retaining the 25 packing in its compressed condition as fast as it yields in response to the pressure applied thereto.

With these general objects in view, as well as minor objects which will appear in the 30 course of the detailed description, the invention will now be described with reference to the accompanying drawing illustrating a form of construction which I have devised for embodying the proposed improvements, after which the features thereof 35 deemed to be novel will be set forth and particularly defined in the appended claims.

In the drawing—

Figure 1 is a vertical sectional view showing the upper portion of a pump apparatus 40 provided with a packing structure embodying the present features of improvement;

Figure 2 is a similar view showing the lower portion of the same apparatus; and

Figures 3 and 4 are transverse sections 45 taken on the lines 3—3 and 4—4, respectively, of Figure 1 (Figure 4 being on an enlarged scale).

Referring in detail to said drawing, this 50 shows a pump construction comprising a plurality of pump tube sections 6 connected by couplings 8, within which tube structure is reciprocated, by any suitable mechanical means, a hollow plunger member made up 55 of tubular sections 10, 12, connected by a

bushing 14. Above the bushing 14 is located a valve seat 16 supporting a ball check valve 18 opposite openings 20 in the lower end of the pipe section 10. At the lower limit of the plunger's movement is a second 60 ball check valve 22 carried by a valve seat 24 within a cage structure comprising a tube section 26 having outlet openings 29 and provided with a follower 28 actuated by a spring 30 into engagement with the valve 22, 65 the top of said tube section 26 being fitted with a plug 32. The parts of the lower check valve are carried by a casting 34 retained in place by the lower coupling 8, said casting 34 forming the connection to a screen 70 construction for the bottom of the pump apparatus, the details of which screen are omitted since the same form no part of the present invention.

Between the two lower pump tube sections 6 is provided a packing cup 36 retained in place by the coupling 8 at this point, said cup 36 serving as the fixed support for a supply of suitable packing 38 between the tube sections 6 and the plunger member. 80 Mounting above said packing 38 is a movable cup section or follower member 40 with the top face of which is engaged a ratchet sleeve 42 of appropriate length and slidingly fitting the plunger member. The upper end 85 of this sleeve 42 is provided with a series of rings 44 of suitable flexible material such as leather and having relatively thin and tapered lip portions for engagement with the inner face of the pipe section 6 in the manner illustrated in Figure 1, said rings 44 being secured in place by means of collars 46 secured on the upper end of the sleeve 42. The arrangement and construction are such 90 as to adapt the weight of the liquid between the pumping tube and plunger to be received by the cup formation at the upper end of the sleeve 42 and transmit the force of said weight through the sleeve and follower 40 to the packing and thereby compress said 95 packing. The upper end of the sleeve is also adapted to be engaged by an enlarged portion 48 formed on the bushing 14, whereby the weight of the plunger may, on sufficient lowering of the same, be utilized to 100 compress the packing through pressure applied to said sleeve 42 and transmitted thereby to the packing.

Latching means is also provided for engaging the sleeve and automatically latching 110

the same as fast as it is depressed by the force or pressure applied thereto. This means comprises a series of ratchet elements 50 movably mounted within a recessed casting 52 retained by one of the couplings 8 in position surrounding the ratchet sleeve 42.

If desired (though not essential), a coil spring 58 engaged on opposite sides by a pair of follower members 60, 62, may be interposed midway in the packing material 38 for providing a pressure means acting constantly in cooperation with the aforesaid construction to take up any give or relaxation in the packing under working conditions.

It is thus apparent that I have provided an extremely simple but efficient arrangement and construction whereby all the weight of the liquid between the pump tube and plunger is effectively utilized in tightening the packing around the plunger, together with automatic means comprising the spring pawls or ratchets and the ratchet sleeve for maintaining the packing tightened under the pressure of all this weight of the liquid, since the said ratchet construction obviously prevents the sleeve 42 from rising. When the operation of the pump is first started and before the liquid being pumped has filled the tubing, the plunger may be lowered sufficiently below the normal limit of its downward movement to engage the projection 48 with the top of the ratchet sleeve, thereby initially compressing the packing, after which the packing will be kept uniformly packed under a substantially constant pressure throughout the remainder of the pump's operation. The provision of the spring 58 and the intermediate followers 60 and 62 affords an auxiliary pressure means which serves to even out or equalize the application of the pressure, as will be readily understood.

While I have described and illustrated what I now regard as the preferred form of construction for embodying the proposed improvements, I desire to reserve the right to make such formal changes or modifications

as may fairly fall within the scope of the appended claims.

What I claim is:

1. A pump packing construction comprising a pump tube, a plunger operating in said tube, packing surrounding said plunger within said tube, a fixed packing cup supporting said packing, a follower member embracing the top of said packing, and flexible cup means supported by said follower member in position for receiving the weight of the liquid above said cup means between said tube and plunger and transmitting the force of said weight to compress the packing. 60

2. A pump packing construction comprising a pump tube, a plunger operating in said tube, packing surrounding said plunger within said tube, a fixed packing cup supporting said packing, a follower member embracing the top of said packing, and means associated with said follower member for receiving the weight of the liquid between said tube and plunger above said packing for transmitting the force of said weight to 70 compress the packing, including means for automatically latching said follower member under the pressure so transmitted.

3. A pump packing construction comprising a pump tube, a plunger operating in said tube, packing surrounding said plunger within said tube, a fixed packing cup supporting said packing, a follower member embracing the top of said packing, a ratchet sleeve carried by said follower member and provided with flexible cup means adapted to receive the weight of the liquid between said tube and plunger above said cup means and transmit the force of said weight through said sleeve and follower member to compress 85 the packing, and automatic latch means acting to retain said sleeve against upward movement.

In witness whereof I hereto affix my signature.

HENRY M. GREEN.
